UNITED STATES PATENT OFFICE.

EPHRAIM L. SCHANCK, OF DELAWARE, OHIO.

PORTABLE BARREL-TRUCK.

1,146,527.

Specification of Letters Patent. Patented July 13, 1915.

Application filed February 24, 1913. Serial No. 750,200.

To all whom it may concern:

Be it known that I, EPHRAIM L. SCHANCK, a citizen of the United States, residing at Delaware, in the county of Delaware and State of Ohio, have invented certain new and useful Improvements in Portable Barrel-Trucks, of which the following is a specification.

My invention relates to barrel trucks and is particularly directed to the provision of a truck for depositing a barrel thereon without tilting the same by hand, as is at present the custom.

More specifically, my invention aims to provide a structure which is adapted to be moved adjacent a barrel and which will effect the tilting and depositing of the barrel upon its carriage by means especially provided for this purpose.

In its preferred form, my invention comprises a wheeled platform carriage having a handle element pivoted thereto. This handle element carries a movable toothed member which is adapted to grip and tilt the barrel by an upward movement of the handle when the carriage has been moved adjacent to the barrel.

Another feature of my invention resides in eccentrically mounting a pair of rollers on the pivoted ends of the handle element in a manner that when the handle is swung upwardly preparatory to loading a barrel on to the carriage, the carriage itself will be lowered to a position of almost resting directly upon the floor. From this, it will be apparent that the barrel will not have to be tilted to any great degree to permit the sliding thereunder of the carriage.

The preferred embodiment of my invention is shown in the accompanying drawings, in which similar characters of reference designate corresponding parts, and in which:

Figure 1 is a side elevation of my preferred type of portable barrel truck, Fig. 2 is a plan view of the structure shown in Fig. 1, Fig. 3 is a detail view of a particular type of connection between the handle element of my truck and its platform carriage, and, Fig. 4 is a plan view of the connection shown in Fig. 3.

In the drawings, I have shown the plat-

form carriage as comprising crossed straps 1 and 2, each having an upturned pierced ear 3, through which is adapted to pass the angular portions 4 and 5 of a rod 6 forming the seating framework of the carriage. This rod 6 is doubled upon itself as indicated at 7, at which point it is supported by the caster 8. The handle of the truck is formed from a bar 9 bent to substantially U-shape and forged to give a circular gripping portion 10. The legs 11 and 12 of the handle member are each terminated short of the portions 4 and 5 as indicated at 13 and 14 and are each provided with a supplemental strip 15 securely fastened to their inner faces and apertured at their lower ends to engage the angular portions 4 and 5 of the rod 6. The outer faces of the legs 11 and 12 are each provided with a casting 16 having a downwardly extending apertured ear 17 adapted to carry the rollers 18. The casting 16 is also apertured to engage the angular portions 4 and 5 of the rod 6 and thereby completes the pivotal connection of the handle 9 with the platform carriage. It will be noted that the castings 16 upon the outer faces of the legs 11 and 12 and the supplemental strip 15 upon their inner faces, provide a space equal to the thickness of each leg for the rotatable operation of the rollers 18 and the castings 16 which are riveted to the handle portion by means of the rivet 19 and are also held in engagement therewith by the bolt and nut structure 20 adapted to also pass through the supplemental strips 15 and support angular stops 21 designed to bear against the forward end of the rod 6 to hold the handle 9 in a predetermined position of angularity. A U-shaped spanning member 22 having a series of jaw teeth 23 is pivotally connected at 24 to slide members 25 slidably upon the legs 11 and 12 of the handle. The links 26 are also pivotally connected at 27 to the legs 11 and 12 and also at 28 to the U-shaped spanning member.

The operation of my device is as follows: The platform carriage is moved to a position adjacent the barrel to be transported and the spanning member 22 moved to the position indicated in full lines in Fig. 1, the spanning member being supported in this

position by the engagement of the lower ends of the links 26 with the upper ends of the strips 15 as shown in Fig. 2. The foot of the operator is placed upon the caster 8 and at the same time exerting a slight forward pressure thereon. Upward swinging of the handle 9 about its pivotal connection will bring the toothed portion 23 into gripping engagement with the barrel. The normal weight of the barrel is sufficient to prevent its sliding along the floor, and continued upward pressure upon the handle will consequently slightly tilt the barrel in a forward direction, whereupon the forward pressure of the foot upon the caster 8 will naturally slide the platform carriage in a position to receive the barrel. If the handle 9 had been left in its upwardly swung position, sliding of the carriage to a position beneath the tilted barrel, would also mean moving the handle as a whole in a forward direction and consequently causing a further tilting of the barrel. This is not desired and the natural tendency on the part of the operator would be to gradually withdraw the handle as the carriage is moved in a forward direction, care being taken by him to withdraw the handle just fast enough to maintain the proper degree of inclination of the barrel. When the barrel is thus about properly located over the carriage and still slightly inclined, the withdrawing of the handle is temporarily discontinued, and an additional forward push on the truck as a whole, will mean that either the barrel must be bodily moved over the floor or the connection formed by the spanning member 22 and the links 26 will yield rearwardly. Inasmuch as the barrel must be of considerable weight, the links 26 move rearwardly about their pivotal connections 27, since the handle by this time has been moved to almost assume the position shown in Fig. 1 causing a temporary slight greater inclination of the barrel as the links 26 pass their dead center position, but eventually assuming the position shown in broken lines in Fig. 1, in which position the barrel will have been deposited upon and supported by the crossed straps 1 and 2. The handle 9 may then be swung back the remaining distance into its normal position and the truck pushed to its desired location.

Removal of the barrel from the truck is accomplished in much the same manner as its loading, except that the spanning member 22 may be left in the position indicated by the dash lines, the forward swinging of the handle being sufficient to tilt the barrel off the carriage and the rearward movement of the carriage itself being the natural result of the forward pressure exerted upon the handle.

It will also be noted that the eccentric 65 mounting of the rollers 18 upon the handle, will permit the platform carriage to assume a position in close proximity to the floor, while the handle is in its forward position and permits the ready sliding thereunder of 70 the carriage and at the same time will slightly tilt the carriage to permit the ready removal of the barrel. This eccentric mounting may be made so that the carriage will have a slightly inclined position when 75 in operative position to be moved across the floor and in this manner prevent accidental removal of the barrel during the transporting action.

It will also be apparent that I have provided a barrel truck having a self supporting carriage, that is, a carriage having a sufficient number of bearing points with the floor so as not to require the assistance of an operator to maintain it in its operative position. 80

What I claim, is:

1. A barrel truck comprising a platform carriage adapted to be moved along the floor, a handle pivoted to said carriage, 90 and means carried by said handle arranged when the carriage is moved adjacent a barrel to engage and tilt the barrel upon an upward swing of the handle to permit the sliding thereunder of the carriage, said means being effective to deposit the barrel on the carriage. 95

2. A barrel truck comprising a wheeled platform carriage adapted to be moved along the floor, a handle pivoted to each side of said carriage, and a toothed spanning member movably mounted on said handle and arranged when the carriage is moved adjacent a barrel to engage and tilt the barrel upon an upward swing of the handle to 100 permit the sliding thereunder of the carriage, said member being then movable away from the tilted barrel to permit its assuming an upright position on the carriage. 110

3. A barrel truck comprising a wheeled platform carriage adapted to be moved along the floor, a handle pivoted to each side of the fore part of said carriage, rollers eccentrically mounted on the pivoted ends of 115 said handle, and a toothed spanning member movably mounted on said handle and arranged when the carriage is moved adjacent a barrel to engage and tilt the barrel upon an upward swing of the handle to permit the sliding thereunder of the carriage, said member being then movable away from the tilted barrel to permit its assuming an upright position on the carriage. 120

4. A barrel truck comprising a wheeled 125 platform carriage, a U-shaped handle embracing the fore part of said carriage and pivoted thereto, rollers eccentrically mount-

ed on the pivoted ends of said handle, slide members on both legs of said handle, a toothed spanning member pivotally mounted on said slide members, and links pivoted to each leg of said handle at one end and to said spanning member at their opposite ends.

In testimony whereof I affix my signature in presence of two witnesses.

EPHRAIM L. SCHANCK.
